Application October 18, 1932, Serial No. 638,323

12 Claims. (Cl. 250—20)

My present invention relates to amplifier gain control circuits and more particularly to an automatic control arrangement adapted for use in connection with amplifiers.

One of the main objects of my present invention is to provide an improved type of automatic gain control system for low or high frequency amplifiers, which system is of the general type utilizing a linear electron discharge control tube. Since a system of automatic amplifier gain control should only function when the signal voltage applied to the detector reaches a certain desired value, and then operate to prevent this detector voltage increasing above this value, the characteristic of such an automatic control should be non-linear. Since it is desirable to make the characteristic of the detector of a receiver as nearly linear as possible, it is therefore preferable to employ a non-linear electron discharge tube device between the detector and the amplifier to be controlled. In general, such a combination of a non-linear electron discharge control tube, furnishing grid bias to a radio frequency amplifier for controlling the gain thereof, and a detector is known. However, in the present application there are disclosed various improvements in such known arrangements, and these improvements comprise, as stated heretofore, one of the main objects of this invention. Another important object of the present invention is to provide a method of controlling the radio gain in a radio receiver by utilizing a direct current voltage furnished by the detector, and amplifying this voltage with a direct current amplifier which may be non-linear, thus permitting the use of a linear detector and a non-linear direct current amplifier in an automatic gain control system for a radio receiver, such a system being highly desirable in view of the fact that the efficiency of the direct current amplifier makes the gain control system highly sensitive.

Another important object of the present invention is to provide a detector arrangement in a radio receiver wherein the drop of potential across an impedance path in the detector cathode is utilized for obtaining a radio frequency bias control voltage, a direct current amplifier being arranged to amplify the drop of potential across said cathode impedance path, and the amplified potential drop being utilized as the radio frequency amplifier gain control voltage.

Another object of the present invention is to provide an automatic gain control system employing a detector arranged for cooperation with a direct current amplifier adapted to amplify the

direct current component of the detector output, the amplifier and detector circuits being arranged for energization from a single unit voltage supply, the direct current amplifier being of the screen grid type and having an impedance in its anode circuit connected to the radio frequency grids to be controlled in such a manner that the grid of the first radio frequency stage is biased more than the grid of one or more succeeding stages.

Still another object of the present invention is to provide an automatic volume control system for a radio receiver wherein the direct current component of the detector output is amplified in a direct current amplifier of the screen grid type, the screen electrode of the amplifier being connected to a point in the detector cathode circuit, and one or more input electrodes of the radio frequency stages being connected to an impedance in the anode circuit of the direct current amplifier.

And still other objects of the invention are to improve generally the simplicity and efficiency of automatic gain control devices, and to particularly provide a radio frequency gain control system of the type using a direct current amplifier in conjunction with the detector output which is not only economical, durable and reliable in operation, but economically manufactured and assembled.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,
Fig. 1 diagrammatically shows a receiver embodying the present invention,

Fig. 2 shows a modified form of the invention, and

Figs. 3 to 6 inclusive each show different modifications of the invention.

Referring now to the accompanying drawings wherein like reference characters designate similar circuit elements in the different figures, the invention is first described in connection with Fig. 2, in order to point out the general principles underlying the present invention. In this figure is shown in diagrammatic manner an arrangement for automatically controlling the gain

of one or more stages of radio frequency amplification, the figure showing only the detector tube 1, and the automatic volume control tube (A. V. C.) 2 in order to preserve simplicity of description.

5 The control voltage for the radio frequency grids is provided by the resistor R, the lead 3 connected to the negative side of the resistor R being connected to the grids of the radio frequency tubes. The control tube 2 is of the indirectly heated cathode type, and has its cathode connected by a lead 4, terminating in a slider 5, to a point of about +40 volts on the voltage supply potentiometer connected between terminals 10 +B and -B. The anode of tube 2 is connected through the resistor R to the grounded conductor 6 which is connected to a point on the voltage supply potentiometer of about +80 volts.

20 The anode of the detector tube 1 is connected to the audio frequency system in any manner well known to those skilled in the art, and the cathode of the detector tube is connected by means of a lead 7, including a grid bias resistor 25 R₁ in series therein, to the negative terminal -B of the voltage supply potentiometer. The grid of tube 2 is connected by a lead 8 to a point a between the positive terminal of resistor R₁ and the cathode of the detector tube. Between the 30 detector grid and the negative side of the resistor R₁ is connected a tunable input circuit 9 which includes a variable tuning condenser 10, it being clearly understood that the circuit 9 is to be coupled to the output of a preceding amplifier, 35 whether it be a tuned radio frequency amplifier of a plurality of stages, or the intermediate frequency amplifier of a superheterodyne receiver. The resistor R₁ is shunted by an audio frequency by-pass condenser 11.

40 As pointed out heretofore, the present gain control system utilizes the voltage drop across a resistor in the cathode circuit of the detector for controlling the gain of the radio frequency stages, the voltage drop being amplified by means 45 of a direct current amplifier prior to utilization in connection with the radio frequency stages. Thus, the drop of potential across the resistor R₁ of the detector tube 1 is utilized for this purpose. This voltage drop increases approximately 50 linearly with the signal voltage impressed on the grid of tube 1. The volume control tube 2 increases the current through the resistor R when the potential drop across the resistor R₁ reaches a proper value, and the voltage drop across the 55 resistor R is then impressed as a control voltage on the radio frequency amplifier grids.

The slider 5 serves to regulate the bias adjustment for the automatic volume control tube 2, and thus sets the level at which the radio frequency detector voltage is held. No current flows through the control tube plate circuit when 60 no radio frequency signal voltage is on the detector grid. When this voltage increases to a predetermined value, the direct current through 65 the detector bias resistance R₁ increases by a certain value which decreases the bias on the control tube, and permits current to flow through the resistor R, thus biasing the radio frequency amplifier tubes and holding the detector signal 70 input voltage substantially constant.

75 While in Fig. 2 the lead 8 has been shown as fixedly connected to point a in the cathode circuit of detector tube 1, it is to be understood that only a portion of the drop across resistor R₁ may be used to operate the control tube 2. Thus, it

is to be clearly understood that the point a may be, if desired, the end of a slider adapted to be adjustably connected to the resistor R₁. In that case the sensitivity of the control tube 2 could be readily adjusted. Also, the cut-off level could 5 be adjusted by either the slider 5 or the point a, and either of these could then be used as a manual volume control if desired. This type of direct current amplifier gain control has the advantage that it is operated more nearly by actual carrier 10 level and is less affected by modulation, this being true especially for high carrier voltages on the detector, since the direct current bias of the detector becomes more nearly linear in its variation with respect to the detector radio frequency 15 carrier voltage with high carrier voltages.

In Fig. 1 is shown a conventional type of radio receiver embodying the arrangement shown in Fig. 2, with certain modifications. The receiver comprises the usual radio frequency amplifier 20 tubes 12, 13, followed by a screen grid detector tube 14, the control tube 15 also being of the screen grid type. A voltage supply potentiometer is shown connected between terminals +B and -B, a point on the potentiometer, having a potential of about +50 volts, being connected to ground through a conductor 16, the latter functioning as the ground line of the receiver. The anode of tube 12 is connected to a proper point 25 of positive potential on the supply potentiometer through the primary coil of the coupling transformer M, and the screen grid electrode is similarly connected to a point of less positive potential on the voltage supply potentiometer.

30 The cathode of tube 12, as well as the cathode of tube 13, is grounded by connection to the lead 16, and includes a grid bias resistor R₂. The variable tuning condensers C in each of the input circuits of tubes 12, 13 and 14 have their rotors 35 grounded by connection to lead 16. A conventional uni-control arrangement 17, shown in dotted lines, is shown connected to the three tuning condensers, it being understood that any desired type of mechanical uni-control arrangement 40 may be used for simultaneously operating 45 these tuning condensers.

The control grid of tube 12 is connected to the ground lead 16 through a coil 18 in series with a resistor 19, the usual antenna circuit 20 being adjustably connected to the resistor 19 to provide a proper input point to the stage including tube 12. The anode and screen grid circuits of tube 13 are energized from the voltage supply potentiometer in a manner similar to that described in connection with tube 12. The coupling transformer M₁ is utilized to couple the anode circuit of tube 13 to the tunable input circuit of detector tube 14. The control grid of tube 14 is coupled to the high potential side of its tunable input circuit through a signal coupling condenser.

55 The coupling condenser has a magnitude of about 0.0001 microfarad while the anode of the tube is connected to a point on the supply potentiometer having a potential of about +230 v. 60 through a path which includes the choke coil 21, having a magnitude of about 10 mh., and the primary coil 22 of the audio frequency coupling transformer M₂. The secondary coil of the transformer M₂ is arranged for connection to any well 65 known type of push-pull power amplifier stage.

70 Each side of the choke coil 21 is connected to the grounded lead 16 through a condenser 23, each condenser having a magnitude of about 0.0001 microfarad. The screen grid electrode of 75

tube 14 is connected through a lead 24 to a point on the supply potentiometer having a potential of about +125 volts. The cathode of detector tube 14 is connected through a path which includes the lead 25, the resistor R₁ and the lead 26 to terminal -B of the supply potentiometer. The resistor R₁ functions as the detector grid bias resistor, has a value of about 25,000 ohms, and is adapted to furnish a bias of -10 to -30 volts.

10 The grid of detector tube 14 is connected through a resistor R₂, having a magnitude of about 2 megohms, and lead 27 to the negative side of the resistor R₁.

The potentials for the various electrodes of the control tube 15 are obtained by connecting a secondary potentiometer between point X on lead 24 and point X₁ on lead 26. The screen grid electrode of tube 15 is connected to a point A of a potential of about +30 volts on the secondary potentiometer, the resistor 28 between points X and A having a magnitude of about 10,000 ohms; the resistor 29 between points A and Y having a magnitude of about 500 ohms; the resistor 30 between points Y and Z having a magnitude of about 1,500 ohms; while the resistor 31 between points Z and X₁ has a magnitude of about 1,000 ohms.

The cathode of control tube 15 is connected for adjustable movement between points Z and Y on resistor 30, and functions as a manual volume control instrumentality for the receiver. The slider 32 is arranged in any well known manner to be adjusted between these last two mentioned points, it being pointed out that the point X₁ is at a potential of zero volts; the point Z is at a potential of +10 volts; while the point Y is at a potential of +25 volts.

The anode of control tube 15 is connected by a lead 33 to the negative terminal of the control bias resistor R which has a magnitude of about 75,000 ohms, the positive side of the resistor R being connected, through the ground lead 16 and resistor B, to the cathode of tube 15. The negative terminal of resistor R is connected by a lead 34 to the low potential side of coil 18. Thus the negative side of resistor R is connected to the grid of radio amplifier tube 12, while the grid of tube 13 is connected through a lead 35 to a point on the resistor R which divides the resistor R into two portions. The upper portion b has a magnitude of about 50,000 ohms, while the lower portion e has a magnitude of about 25,000 ohms. It will, thus, be seen that the control bias on the grid of tube 12 is different from, and greater than, the control bias applied to the grid of amplifier tube 13. The function of this differential control biasing will be explained hereinafter.

The control electrode of tube 15 is connected to the positive side of the resistor R₁. The potential drop across this latter resistor furnishes the grid bias voltage for the detector tube 14, and also varies the grid bias voltage for the control tube 15. The tube 15 amplifies the drop across the resistor R₁ and the varying potential drop across resistor R, due to the variation in plate current of control tube 15, functions to automatically control the gain of the amplifier stages including tubes 12 and 13. Of course, the voltage supply potentiometer can be connected to a direct current supply source, or may be connected to the output of the usual filtered rectified alternating current source. The various control grid, cathode, screen grid and anode circuits in the radio frequency and detector stages have been shown ap-

propriately by-passed for radio frequency currents by fixed condensers.

The operation of this type of automatic gain control system was found to be satisfactory. The secondary resistance network between points X and X₁, which is shunted across the potentiometer portion B, is necessary to supply the automatic volume control tube 15. If the automatic volume control voltages are obtained directly from portion B a reaction is caused by virtue of the 10 I_p of the radio frequency tubes. This results in a reaction at certain settings of the manual control 15 32 producing a sudden increase in radio frequency bias. By the shunt network X, X₁ this effect is eliminated since in this case a reduction 20 of radio frequency I_p increases the voltage across the network X, X₁ as decreasing radio frequency I_p decreases the current and the IR drop across the portion C₁ of the supply potentiometer. This system, is therefore, perfectly stable. That is, 25 the phase of the reaction of the automatic volume control tube on the supply voltage is reversed over what it is when the automatic volume control tube is supplied directly from the portion B, and these effects can be controlled by adjusting the 25 positions of point X along the potentiometer portion B.

It is believed that the operation of the arrangement shown in Fig. 1, as well as that shown in Fig. 2, will be clear from the foregoing description and the drawings. When the carrier input to the detector, which is of the power detector type, exceeds the desired level giving the desired reproduction volume, the potential drop across the resistor R₁ increases with the result that the bias on the grid of control tube 15 decreases. This results in a greater plate current flow through the plate circuit of tube 15, and a greater drop of potential across the resistor R.

Obviously, then, the negative voltages applied 40 to the grids of tubes 12 and 13 increase, and the amplification in the stages including the tubes 12 and 13 decrease, thus bringing the reproduction volume down to the desired level. If the carrier decreases below the desired level, then the 45 reverse action takes place, and the radio frequency amplification is automatically increased to again provide the predetermined input voltage to the power detector tube 14. Thus, it will be seen that the function of the direct current amplifier tube 15, and its associated circuits, and differential biasing connections to the tubes 12 and 13 is to provide at all times a uniform input voltage supply to the input of power detector tube 14. Such a uniform supply is especially desirable 55 in the case of a power detector which is to operate in a linear fashion.

Accordingly, it will be seen that there is provided by means of the present invention an automatic gain control system wherein a linear power detector is employed for handling the signal energy, and a non-linear direct current amplifier for controlling automatically the gain of the radio frequency stages, it being observed that the drop across the resistor R₁ varies substantially linearly with signal input voltages to the detector tube 14.

The purpose of the differential biasing arrangement of tubes 12 and 13 is clearly disclosed by 70 Stuart Ballantine in application Serial No. 376,163 filed July 5, 1929. Briefly, it may be stated that such an arrangement extends the range of amplification control throughout which distortionless amplification may be obtained.

It has been found experimentally that if the several grids of the radio frequency stages are biased equally, a value of common grid bias is reached at which the relation between the input 5 and the output voltages of the radio frequency amplifier becomes non-linear. In accordance with the said Ballantine invention, the range of gain control of the radio frequency stages is graduated, and the range through which the bias 10 voltage of the second radio frequency stage may be varied is less than the bias voltage range of the first tube. By departing, in the manner shown in Fig. 1, from the prior practice of employing a common control grid bias for all stages, 15 the range of automatic distortionless control is greatly extended for the radio frequency stages.

In Figs. 3 to 6 inclusive are shown modified forms of the invention, the modifications particularly being made in the direct current amplifier portion of the amplifier gain control system. Thus, in Fig. 3 the detector 14 is of the screen grid type, as in Fig. 1, and the circuit arrangement of Fig. 3 is schematically shown in the same manner as in the case of Fig. 2. The control tube 2 is also of the screen grid type, and only those portions of the circuit in Fig. 3 will be described which involve the modification. The cathode of the detector tube 14 is connected to the grid of control tube 2, and both the cathode of tube 14 25 and grid of tube 2 are connected through the detector grid bias resistor R_1 to the $-B$ terminal of the supply potentiometer.

The screen grid of control tube 2 is shown adjustably connected by a lead 40 to a point of +75 35 volts on the supply potentiometer. The anode of control tube 2 is shown connected through the control bias resistor R to the grounded lead 6. The cathode of tube 2 is connected by the slider 5, functioning as a manual volume control or 40 setting device for the radio frequency detector voltage level, to a point in the region of +20 volts of the supply potentiometer.

The operation of the arrangement shown in Fig. 3 is similar to that described in connection with 45 Figs. 1 and 2. The potential drop across resistor R_1 increases or decreases with increasing and decreasing inputs to the detector 14, and the potential drop across resistor R varies in the same manner as the potential drop across resistor R_1 . Thus, there is a device for controlling the input 50 to the detector so that the input is substantially constant. It should be noted that the screen grid of tube 2 may be connected as shown, or connected to the anode thereof thus rendering it 55 possible to use tube 2 as a triode. Of course, the adjustable lead 40 may be connected so that the screen is below plate voltage; that is, it has a normal screen grid operation. The present circuit is very sensitive, and it should also be noted 60 that the grid of the automatic volume control tube may be shifted along the resistor R_1 to set the level of detector voltage or to manually control volume, as well as by controlling the position of slider 5.

Fig. 4 shows a modification where the screen grid of the control tube is used to control its plate current, the screen of control grid tube 2 being connected by a lead 2' to a point between the positive side of the resistor R_1 and the cathode 70 of the detector tube. The control grid of the control tube 2 is connected between the negative side of the resistor R_1 and the $-B$ terminal of the supply potentiometer.

The cathode of the control tube 2 is, again, 75 connected to the supply potentiometer through a

slider 5 which functions to manually control the detector input voltage level. The operation of this modification is similar to that described in connection with Fig. 3, it being noted that the plate current flow through the resistor R is varied 5 by the varying potential on the screen grid of tube 2. If the signal input to the detector increases, the potential on the screen grid of tube 2 increases, with the result that the plate current flow through the resistor R increases, and the radio 10 frequency amplification is, thus, cut down. The arrangement shown in Fig. 4 reduces the necessary B supply voltage to about 30 volts below ground potential for automatic volume control 15 operation.

In Fig. 5 is shown a modification of the arrangement shown in Fig. 4 for use with detectors having higher bias voltage. It will be noted that the control grid of control tube 2 is connected by a lead 5' to the $-B$ terminal of the supply potentiometer, while the plate of the control tube 2 is operated below the screen grid potential to conserve B supply voltage. Otherwise, the operation of this modification is similar to that shown in Fig. 4.

Fig. 6 shows still another modified form of direct current amplifier arrangement, wherein the change in detector plate current is used to change the plate voltage of the direct current amplifier tube. The detector in this case is of the grid leak 30 type. Thus, the anode of the tube 2 is shown connected to a lead 6' which is connected between the positive side of the detector cathode resistor R_1 and a point on the supply potentiometer.

The control grid of tube 2 is connected to the $-B$ side of the potentiometer, while point a' of the supply potentiometer is established as the ground potential by connecting it, through a lead 7', to the negative side of resistor R_1 and grounding it at that side. The cathode of tube 2 is connected to the grounded negative side of resistor R_1 through the control bias resistor R .

It should be noted that the voltage across the resistor R is in reverse direction for what is desired in normal bias volume control. The operation of this modification is based on the fact that the voltage across R_1 in the plate-cathode circuit of the detector decreases with increasing signal inputs. The positive side of resistor R is, 45 therefore, connected to the grids of the radio frequency amplifiers. Of course, the normal fixed bias at no-signal condition on each controlled amplifier will be secured by keeping the amplifier cathode more positive than its grid by the 50 desired bias value. As signal amplitude increases the voltage drop across R_1 decreases; this causing a decreased drop across R and a reduction in the gain of the controlled amplifier by a less positive biasing of the controlled amplifier grid. It is to be noted that instead of connecting the anode of tube 2 to the lead 6' the tube 2 55 could be replaced by a screen grid tube, and the screen grid thereof connected to lead 6' in a manner as shown in connection with the anode of the 60 tube 2.

While I have indicated and described several systems for carrying my invention into effect, it will be apparent to one skilled in the art that my invention is by no means limited to the particular organizations shown and described, but that many modifications may be made without departing from the scope of my invention as set forth in the appended claims.

What I claim is:

1. The combination with a plurality of cascaded amplifier stages whose input circuits are maintained at a common carrier wave potential, of means for varying an amplification controlling voltage applied to each of said stages, said voltage variation means comprising a detector, an input circuit for said detector and shunted across the output of said amplifier stages, said detector being of the self-biased type and including a resistor in its cathode circuit, the detector grid being connected to a point on the resistor which is negative with respect to the detector cathode, a direct current amplifier arranged to amplify the direct current component of the detector output current developed across said detector cathode resistor, and connections between the amplifier stages and the direct current amplifier for applying the output of said direct current amplifier to the cascaded amplifier stages so that the voltage change applied to successive stages is progressively decreased. 5
2. The combination with a plurality of cascaded amplifier stages whose input circuits are maintained at a common carrier wave potential, of means for varying an amplification controlling voltage applied to each of said stages, said voltage variation means comprising a detector, an input circuit for said detector and shunted across the output of said amplifier stages, a direct current amplifier arranged to amplify the direct current component of the detector output current, connections between the amplifier stages and the direct current amplifier for applying the output of said direct current amplifier to the cascaded amplifier stages so that the voltage change applied to successive stages is progressively decreased, said detector including a screen grid tube, a resistor in the cathode circuit of the detector, the input electrodes of the direct current amplifier being connected to the said resistor in the cathode circuit of the detector, the detector grid being connected to a point on said resistor which is negative with respect to the detector cathode, and the anode circuit of the direct current amplifier including a resistor, the potential drop across the latter being employed for said voltage change applied to the successive amplifier stages. 10
3. In combination, a radio frequency amplifier having an input circuit arranged to have impressed thereon signal energy to be amplified, a detector including an impedance in its output circuit whereby the detector space current flows through the impedance, a direct current amplifier having its input electrodes connected across said impedance, the detector grid being connected to a point on said impedance which is negative with respect to the detector cathode, an impedance in the output circuit of said direct current amplifier, connections between said first amplifier and said anode impedance for applying a control bias to the grid of said first named signal energy amplifier, and a common voltage supply potentiometer for energizing the electrodes of said signal energy amplifier, detector and direct current amplifier. 15
4. In combination, a radio frequency amplifier having an input circuit arranged to have impressed thereon signal energy to be amplified, a detector including an impedance in its output circuit whereby the detector space current flows through the impedance, a direct current amplifier having its input electrodes connected across said impedance, the detector grid being connected to a point on said impedance which is negative with respect to the detector cathode, an impedance in the output circuit of said direct current amplifier, connections between said first amplifier and said anode impedance for applying a control bias to the grid of said first named signal energy amplifier, a common voltage supply potentiometer for energizing the electrodes of said signal energy amplifier, detector and direct current amplifier including an adjustable slider in its cathode circuit, the slider being arranged for adjustment over a portion of said potentiometer. 20
5. In combination, a radio frequency amplifier having an input circuit arranged to have impressed thereon signal energy to be amplified, a detector including an impedance in its output circuit whereby the detector space current flows through the impedance, a direct current amplifier having its input electrodes connected across said impedance, the detector grid being connected to a point on said impedance which is negative with respect to the detector cathode, an impedance in the output circuit of said direct current amplifier, connections between said first amplifier and said anode impedance for applying a control bias to the grid of said first named signal energy amplifier, a common voltage supply potentiometer for energizing the electrodes of said signal energy amplifier, detector and direct current amplifier including a screen grid tube, and said direct current amplifier comprising a screen grid tube, the screen grid and cathode of the direct current amplifier being adjustably connected to said voltage supply potentiometer. 25
6. In combination, with a radio frequency amplifier arranged to have its gain automatically controlled, a detector, an impedance in the cathode circuit of the detector, a direct current amplifier comprising a screen grid tube, means for connecting the screen electrode of the direct current amplifier to one side of said impedance, and the grid and cathode to the other side of said impedance, an impedance in the anode circuit of the direct current amplifier, and means for connecting the low potential side of said anode impedance to an input electrode of said amplifier to be controlled. 30
7. In combination with a radio frequency amplifier arranged to have its gain automatically controlled, a detector, an impedance in the cathode circuit of the detector, a direct current amplifier comprising a screen grid tube, means for connecting the screen electrode of the direct current amplifier to one side of said impedance, and the grid and cathode to the other side of said impedance, an impedance in the anode circuit of the direct current amplifier, means for connecting the low potential side of said anode impedance to an input electrode of said amplifier to be controlled, and a common potential supply potentiometer connected to energize the circuits of said detector and direct current amplifier tubes. 35
8. In combination, in a radio receiver, a power detector stage including a screen grid tube, a multi-stage radio frequency amplifier arranged to supply a relatively high radio frequency signal voltage to the input of said screen grid detector, a common supply voltage potentiometer for energizing the circuits of said multi-stage amplifier and power detector, means in the output circuit of said power detector arranged for connection to a power amplifier stage, an impedance in the cathode circuit of said screen grid tube. 40

grid detector tube, the detector grid being connected to a point on said impedance which is negative with respect to the detector cathode potential to insure linear operation of the detector, a direct current screen grid amplifier having its electrodes connected to said potentiometer for energization therefrom, the control grid and cathode of said direct current amplifier being connected across said impedance, an impedance in the anode circuit of the direct current amplifier, and connections between said anode circuit impedance and the grids of said multi-stage amplifier for applying control biases to said grids which progressively decrease for each successive stage.

9. In combination, in a radio receiver, a power detector stage including a screen grid tube, a multi-stage radio frequency amplifier arranged to supply a relatively high radio frequency signal voltage to the input of said screen grid detector, a common supply voltage potentiometer for energizing the circuits of said multi-stage amplifier and power detector, means in the output circuit of said power detector arranged for connection to a power amplifier stage, an impedance in the cathode circuit of said screen grid detector tube, the detector grid being connected to a point on said impedance which is negative with respect to the detector cathode potential to insure linear operation of the detector, a direct current screen grid amplifier having its electrodes connected to said potentiometer for energization therefrom, the control grid and cathode of said direct current amplifier being connected across said impedance, an impedance in the anode circuit of the direct current amplifier, connections between said anode circuit impedance and the grids of said multi-stage amplifier for applying control biases to said grids which progressively decreases for each successive stage, and means for adjustably connecting the cathode of said direct current amplifier to said potentiometer.

10. In combination, in a radio receiver, a power detector stage including a screen grid tube, a multi-stage radio frequency amplifier arranged to supply a relatively high radio frequency signal voltage to the input of said screen grid detector, a common supply voltage potentiometer for energizing the circuits of said multi-stage amplifier and power detector, means in the output circuit of said power detector arranged for connection to a power amplifier stage, an impedance in the cathode circuit of said screen grid detector tube, the detector grid being connected to a point on said impedance which is negative with respect to the detector cathode potential to insure linear operation of the detector, a direct current screen grid amplifier having its electrodes connected to said potentiometer for energization therefrom, the con-

trol grid and cathode of said direct current amplifier being connected across said impedance, an impedance in the anode circuit of the direct current amplifier, connections between said anode circuit impedance and the grids of said multi-stage amplifier for applying control biases to said grids which progressively decrease for each successive stage, the connection between the electrodes of said direct current amplifier and said potentiometer including a secondary potentiometer in shunt with said first named potentiometer.

11. In combination, in a radio receiver, a power detector stage including a screen grid tube, a multi-stage radio frequency amplifier arranged to supply a relatively high radio frequency signal voltage to the input of said screen grid detector, a common supply voltage potentiometer for energizing the circuits of said multi-stage amplifier and power detector, means in the output circuit of said power detector arranged for connection to a power amplifier stage, an impedance in the cathode circuit of said screen grid detector tube, the detector grid being connected to a point on said impedance which is negative with respect to the detector cathode potential to insure linear operation of the detector, a direct current screen grid amplifier, having its electrodes connected to said potentiometer for energization therefrom, the control grid and cathode of said direct current amplifier being connected across said impedance, an impedance in the anode circuit of the direct current amplifier, connections between said anode circuit impedance and the grids of said multi-stage amplifier for applying control biases to said grids which progressively decreases for each successive stage, and manually operated means connected to one of the input electrodes of said direct current amplifier for setting the detector input voltage level.

12. In a radio receiver of the type which includes a radio frequency amplifier and a detector network provided with a tube having a resistor in its cathode circuit, the improvement which comprises a gain control tube having a cathode, anode and at least one auxiliary cold electrode, said cathode and auxiliary electrode being connected to points of different potential on said resistor, an impedance in the anode circuit of said control tube, amplifier gain control connections between the amplifier and said impedance, said points on the resistor being chosen to cause the space current flow of said control tube to increase with increase of signal amplitude, and the detector grid being connected to a point on the resistor which is negative with respect to the detector cathode potential whereby the detector operates as a biased detector.
